APPARATUS FOR CONTROLLING OIL AND GAS WELLS

Filed April 15, 1930

James F. Bower INVENTOR

UNITED STATES PATENT OFFICE

JAMES F. BOWER, OF OKLAHOMA CITY, OKLAHOMA

APPARATUS FOR CONTROLLING OIL AND GAS WELLS

Application filed April 15, 1930. Serial No. 444,412.

My invention relates to improvements in devices for controlling the flow of gas and oil from deep wells under high pressure which are flowing wild and out of control.

The principal objects of my invention are to provide a device of this character which is new, novel, practical, useful, and of evident utility; which is strong, positive in action, durable and reliable; which consists of but few sturdy parts, is easily applied and operated, cannot easily get out of order and is efficient for the purposes for which it is intended; to provide a controlling apparatus the anchoring means of which is adapted to be clamped around the well casing below the open end through which the production is escaping and which may be secured to the floor or walls of the cellar by cable lines; a device so anchored to external supports as to relieve the casing of the pressure-load due to the final closing of the well; to provide an apparatus capable of being seated over the end of a casing devoid of threads or even broken off with a jagged fracture; a device having a hinged hood or bonnet with interior conical taper adapted to be swung over the open end of the well casing from one side and then drawn down by powerful adjusting screws to a closing fit; a device in which said hood member is provided with an open mouth having a sharp lip adapted to deflect the stream of oil and gas into and through said hood with very little obstruction to said stream as the hood is being swung into position over the casing; a device adapted for connecting with casing nipples and master gate valves for final closing in of the well; an apparatus capable of being seated on the casing, anchored to the cellar and swung into place entirely independent of the derrick so that it may be successfully used even if the derrick has been destroyed.

The method now used to control a well flowing wild is to assemble couplings, nipples, valves and pipes, raise this massive assembly above the heavy flow of gas and oil and then lower the said assembly squarely over the open casing, stabbing it down until connection is made and the assembly is screwed into place. There is great danger

that sparks may result from said assembly striking the casing and setting the gas on fire, thus involving an immense fire hazard. This method also requires the use of a derrick, and cannot be used in case the derrick has been destroyed.

My improved device eliminates these defects by reason of the fact that my hood becomes an integral part of the casing and the vibration so detrimental to screw threads on the end of the casing has no effect to loosen my hood connection.

With these and other objects in view as will more fully appear my invention consists of the construction, novel features, and combination of parts more fully described, pointed out in the claims hereto appended, and illustrated in the accompanying one-sheet drawings, of which,

Figure 1 is a front elevation of my apparatus partly in section and broken away; Fig. 2 is a side elevation partly in section; and Fig. 3 is a perspective view of my support collar.

Like characters of reference designate like parts in all the figures.

It is understood that various changes in the form, proportion, size, shape, weight, and other details of construction, within the scope of my invention may be resorted to without departing from the spirit or broad principle of my invention and without sacrificing any of the advantages thereof, and that the drawings are to be interpreted as being illustrative and not restrictive.

One embodiment of my invention is shown as follows: The numeral 1 represents the well casing the open end of which is shown at 2. My flanged clamps 3 are provided with holes 4 for attaching cables 5 adapted to anchor said clamps to the cellar walls or floor. Clamp bolts 6 secure clamps 3 in position on said casing 1. The inner surface of clamps 3 which contacts said casing 1 may be milled and roughened the better to grip said casing 1 but I do not depend upon this except as auxiliary anchorage for cables 5 will secure my device against upward movement. I provide a plurality of perforated lugs 7 on said clamps 3 through which I pass

my powerful adjusting screws 8. Adjusting nuts 9 are positioned on said screws 8 between said lugs 7 and said screws 8 and nuts 9 may be fixed in any desired position by lock nuts 10. The upper ends of screws 8 terminate in hinge connections 11 adapted to seat on wrist pins 13 on hinge arms 12. Nuts 14 on said pins 13 seat on a shoulder on said pins 13 and provide a secure, free-acting hinge joint. My support collar 15 consists of member 16 having hook ends 18 adapted to seat under connection 11 and partially enclose adjusting screw 8 when in its extended position as can best be seen in Fig. 2. 5

Clamping member 17 of collar 15 together with bolts 19 provide a slidable connection to casing 1. As shown in Fig. 2 my support collar 15 will resist a force acting on connection 11 in one direction only. It can 10 readily be understood that by using another collar 15 below the one shown but turned in the opposite direction my connection 11 will be held securely against forces acting both forward and backward. Hinge arms 12 15 form an integral part of my hood 20 having an interior conical taper 21 forming a bottle neck at 22. The lower front wall is cut away to form an open mouth 23 provided with a knife edge 24. The back wall 25 extends below said mouth 23 and is adapted to seat against the wrapped packing 26 adjacent the open end 2 of casing 1. Casing nipple 27 is in threaded connection at 28 with said hood 20 and seats on shoulder 29 20 in said hood 20 forming a smooth, unobstructed connection with bottle-neck 22. Master gate valve 30 is secured to said nipple 27 and nipple 31, said nipple 31 may have other valves and connections as may be deemed necessary but which form no part of 25 my invention. To said nipple 31 I attach casing clamp 32 provided with rings 33 and 34. Having clamp 32 attached as shown in Fig. 2, provides ample leverage for swinging 30 my apparatus over the open end 2 of casing 1 by means of block and tackle 35 attached to ring 34 and eased over by block and tackle 36 attached to ring 33. The said blocks and tackle 35 and 36 can be anchored 35 to deadmen buried beyond the derrick base at angles of 120 degrees, more or less, from each other and thus no part of my apparatus is dependent upon the derrick for assistance. 40

In installing and using my apparatus, clamps 3 are positioned on casing 1 at the proper distance below end 2 thereof, two members 16 of collars 15 are placed on top of said clamps 3, said members 16 facing in opposite directions and having hooks 18 in alinement with the perforations in lugs 7. 45 adjusting nuts 9 are placed between said lugs 7, adjusting screws 8 previously secured to hinge arms 12 are slipped down through said members 16, said upper lugs 7 and into con- 50 tact with nuts 9. Nuts 9 are screwed up until screws 8 are through lower lugs 7, cables 5 are made taut, clamping members 17 of collars 15 are placed in position, said collars 15 are seated and clamped under hinge connection 11. My hood 20 and its nipple and valve connections will be in a recumbent position to one side of casing 1, the space immediately below the open end 2 of casing 1 will now be wrapped with hydraulic packing 26 of any suitable kind. Hood 20 and its connections will be raised to a semi-erect position, blocks and tackle 35 and 36 will be secured to their respective anchorages and said hood 20 will be swung forward until knife edge 24 enters the stream 37 of oil or gas and deflects said stream 37 into and through bottle neck 22 and casing nipple 27. Master gate valve 30 being wide open will offer no resistance to the passage of said stream 37. When hood 20 and its connections are vertically above casing 1, edge 25 of hood 20 will be in perfect alinement with screws 8. Support collars 15 will be released and allowed to slide down and seat on top of clamps 3, nuts 9 will be brought into action and hood 20 will be forced down over packing 26 and end 2 of casing 1 until said casing 1 and packing 26 are tightly wedged into the conical taper 21 above knife edge 24 in bottle neck 22, lock nuts 10 will then be seated under lower lugs 7 and fix screws 8 in any desired position. My adjusting screws 8 can be made so powerful that the end 2 of casing 1 can be crushed within the heavy walls of my hood 20 and said end 2 may be devoid of threads and broken off with a jagged fracture and I can still secure a perfectly tight joint. At this stage the master gate valve can be closed and the well will be under control. 55

Having thus described my device what I claim as new and wish to secure by Letters Patent is:

1. In a device of the class described the combination of clamps adapted for encompassing a well casing and seating from the sides of said casing, flanges on said clamps, anchoring means on said flanges, a plurality of perforated lugs on said clamps, adjusting nuts adapted for seating between said lugs, adjusting screws suitable for passing through said perforated lugs and being actuated by said nuts, a hood member, hinge arm bifurcation on said hood and articulating means between said hinge arms and said adjusting screws. 60
2. In a device of the class described, the combination of clamps adapted for encompassing a well casing and seating from the sides of said casing, flanges on said clamps, anchoring means on said flanges, a plurality of perforated lugs on said clamps, adjusting nuts adapted for seating between said lugs, adjusting screws suitable for passing through said perforated lugs and being actuated by 65

- 5 said nuts, a hood member, hinge arm bifurcation on said hood, articulating means between said hinge arms and said adjusting screws, support collars for said screws slidably clamped to said casing, said hood having an interior conical taper with bottle-neck terminus, an open mouth on the front of said hood provided with a knife edge adapted to deflect a stream of oil and gas into and
- 10 through said hood, threaded connection and shoulder means on said hood for a casing nipple adapted to form a smooth, continuous passage with said bottle-neck, master gate valve and other casing nipple connections above said first nipple, and means for swinging said device into vertical alinement with said stream. 70
- 15 3. In a device of the class described the combination of clamp and anchor means for securing a plurality of powerful adjusting screws to a well casing, slideable support collar means for said screws, a hood having interior conical taper with bottle-neck terminus, bifurcated hinge arms on said hood adapted for co-acting with said collar supported screws, said hood having an open mouth adapted to swing over the open end of a well casing, a downward extending wall on said hood behind said open mouth adapted to seat against the side of said casing when said hood is in vertical alinement with a stream of oil and gas spouting from said casing, a knife edge on said open mouth adapted to direct said stream into and
- 20 35 through said hood, wrapped packing adjacent the open end of said casing, powerful adjusting nuts on said adjusting screws adapted to lower said hood over said casing and seat said casing and said packing within said conical taper in said hood and form a leak-proof joint between said hood and said casing. 80
- 25 40 4. A combination as defined in claim 1, in combination with: sharp lip and conical taper means on said hood for engaging the stream of oil and gas flowing uncontrolled from a well, the said means causing the said stream to automatically pull the said hood and its attached connections into centralized
- 45 50 position above said casing. 95
5. A combination as defined in claim 2, means on said hood for engaging the stream of oil and gas flowing uncontrolled from a well, the said means causing the said stream to hold said hood and its attached connections in position ready to be forced down into engaging position on said casing. 100
- 55 60 6. A combination as defined in claim 1, in combination with: means for securing said hood in fluid-tight contact with said casing and means for controlling the flow of oil and gas through said hood after it has been secured. 110
- 65 7. A combination as defined in claim 3, in combination with: anchoring means on said
